UNITED STATES PATENT OFFICE

2,122,501

REFRIGERATING APPARATUS

Charles C. Thomas, Detroit, Mich., assignor, by
mesne assignments, to Nash-Kelvinator Cor-
poration, Detroit, Mich., a corporation of
Maryland

Application July 28, 1934, Serial No. 737,319

2 Claims. (Cl. 312—186)

My invention relates to refrigerators and more particularly to auxiliary shelves or trays therefor.

It is frequently necessary when placing articles into or removing them from a refrigerator, to rearrange the articles that are in the refrigerator and in doing so to temporarily remove the same. Obviously, it then becomes necessary to place the temporarily removed articles at some other location, such for example as on a table, which may be inconveniently located at some distance from the refrigerator. This oftentimes is a great inconvenience as it consumes time and causes the housewife or other person to take many unnecessary steps.

An object of my invention is to provide a refrigerator with an auxiliary or rearranging shelf or tray which is conveniently mounted such as on the refrigerator door, in such manner that it may be easily disposed in a readily accessible article-receiving and supporting position, and which, when not in use, may be disposed in such position as not to occupy useful space within the refrigerator. Another object of my invention is to provide a refrigerator door having an auxiliary shelf or tray of the character referred to thereon, with a recessed portion for receiving such shelf or tray when the same is disposed in an inoperative position, whereby the shelf or tray will not occupy useful space within the refrigerator when the door is closed.

The present invention, however, both as to its construction and use, together with additional objects and advantages thereof, will best be understood from the following description of specific embodiments when read in conjunction with the accompanying drawing, in which:

Figure 1 is a perspective view showing a refrigerator cabinet, the door being open and having an auxiliary or rearranging shelf of the present invention mounted thereon, the shelf being shown in its operative article-supporting position;

Figure 2 is an enlarged side elevation of the refrigerator door shown in Figure 1, the shelf being disposed in its article-supporting position and also being shown in dotted outline in a partially lowered position;

Figure 3 is a view similar to Figure 2 but with the shelf in its raised inoperative position;

Figure 4 is a fragmentary side elevation of the door shown in Figure 2; and

Figure 5 is a fragmentary top plan view of the door shown in Figure 2.

Referring to the accompanying drawing, in which like numerals refer to like parts through-

out the several views, there is shown in Figure 1, for the purpose of illustration, a refrigerator cabinet 10 having a hinged door 11. The auxiliary or rearranging shelf of the present invention, as here shown in Figures 2 to 5, is in the form of a sheet metal tray 12 having flanges 13 along its ends and front side, each flange 13 terminating in an outwardly extending lip or flange 14. The shelf, however, may be of any other suitable construction such as for example of grille-like construction of the type employed in the refrigerator shelves 15 shown in Figure 1.

The shelf or tray 12 is hinged to the inner face of the door 11 so that it may be swung from a vertical inoperative position adjacent the inner door face, as indicated in Figure 3, to a horizontal article-supporting position, as indicated in Figure 2.

In order, however, that the tray 12 will not occupy useful space within the refrigerator, it is preferred to offset the upper portion of the inner face of the door, as shown in Figure 2, to provide a tray receiving recess 16 and a horizontal ledge 17. The hinges 18 which connect the tray 12 with the door 11 may be secured to this ledge 17 in such manner that when the tray 12 is swung upwardly to its vertical inoperative position, as shown in Figure 3, the bottom thereof will lie substantially in the plane of the lower portion of the inner door face. By forming the inner door face with the recess 16 and hinging the tray 12 in the manner described, it is obvious that the tray, when it is in its inoperative vertical position, will not occupy any of the useful space within the refrigerator after the door is closed.

Any suitable means, such for example as a chain, extensible links, or an arm arranged to disappear between the door panels, may be employed for supporting the tray 12 in its horizontal position. One means for doing this is shown for illustration in Figures 2 to 5, as comprising a pair of pivoted links 20, one of which is pivoted to the end flange 13 of the tray and the other of which is pivoted to a hinge bracket 19 secured to the inner door face above the hinges 18. The links 20, when the tray 12 is swung upwardly, swing about their pivotal axes as shown in dotted outline in Figure 2, and permit free swinging movement of the tray, but act, when the tray is lowered, to provide an efficient supporting structure for the tray.

Any suitable means, such as for example the spring metal latch 20 shown in Figures 1 to 5, may be utilized for retaining the tray in its ver-

tical position. The latch 28 may be disposed as here shown in a depression 21 formed in the upper edge portion of the door 11.

When it is desired to utilize the tray 12 for supporting articles while the articles that may be on the shelves 15 are being rearranged or while other articles are being removed from or placed on the shelves 15, it is merely necessary to lift the resilient latch 28 and swing the tray 12 downwardly to its article-supporting position. Likewise, when it is desired to dispense with the tray 12, it is merely necessary to swing it upwardly until the marginal forward flange 14 is engaged with the downwardly projecting portion 15 of the latch 28.

The tray 12 may be of any suitable size and may even be of such size as to support a serving tray on which it may be desired to place a member of articles.

It will be noted from the drawing and foregoing description that the device of the present invention provides a new and useful means for use with refrigerators which is conveniently disposed for receiving articles while other articles are being placed in or removed from the refrigerator or are being rearranged therein. It will be further noted that the shelf or tray is readily accessible and arranged to be disposed in such manner that it will not occupy useful space in the refrigerator when the door is closed. The auxiliary shelf serves a very useful purpose in that it conserves the time of and eliminates unnecessary movements of the housewife or other person.

Aside from the specific embodiments of the in-

vention herein shown and described, it will be understood that numerous details of the construction may be altered or omitted without departing from the spirit and scope of the invention as disclosed and claimed, and that I do not desire to limit the invention to the exact constructions herein set forth.

What I claim is:

1. The combination in a refrigerator of a door, a recess in the inner face of said door, a tray 10 shaped shelf, a removable transfer tray supported by said shelf and confined within the same, hinge means connecting said shelf with said door at the lower edge of said recess for swinging movement from a horizontal to a vertical position 15 to position said shelf and tray within said recess, resilient latch means carried by the door for securing said shelf in a vertical folded position adjacent the door, and extensible link supports connected with said door and said shelf for holding the latter in a horizontal position. 20

2. The combination in a refrigerator of a door having a recess in the inner face thereof, a removable transfer tray, a shelf having a depression therein for receiving and supporting said tray in substantially confined relation, means for hinging said tray to said door at a horizontal edge of said recess whereby said shelf and tray may be moved from a horizontal position to a vertical position within said recess, means for 25 supporting said shelf in its horizontal position, and means for holding said shelf in its vertical position. 30

CHARLES C. THOMAS.
